BUMPER OVERRIDER EXTENSION

John Vota, Washingtonville, and Manfred Storm, West Haverstraw, N.Y., assignors to Calibur Manufacturing Corp., West Nyack, N.Y.

Filed June 24, 1974, Ser. No. 482,005

Term of patent 14 years

Int. Cl. D12—16

U.S. Cl. D12—172

Fig. 1.

Fig. 2.

Fig. 3.

Fig. 4.

Fig. 5.

FIG. 1 is a left side elevational view of a bumper overrider extension showing our new design;

FIG. 2 is a rear elevational view thereof;

FIG. 3 is a bottom plan view thereof;

FIG. 4 is a top plan view thereof; and

FIG. 5 is a front perspective view illustrating the right side thereof.

We claim:

The ornamental design for a bumper overrider extension, as shown.
